UNITED STATES PATENT OFFICE.

PETRUS KLAAS VAN DER STERR AND ALBERT PHILIPP BENDER, OF FRANKFORT-ON-THE-MAIN, GERMANY, ASSIGNORS, BY MESNE ASSIGNMENTS, TO WESTINGHOUSE ELECTRIC & MANUFACTURING COMPANY, A CORPORATION OF PENNSYLVANIA.

RELAY ARRANGEMENT.

Application filed August 29, 1921. Serial No. 496,675.

To all whom it may concern:

Be it known that we, PETRUS KLAAS VAN DER STERR, a subject of the Queen of Holland, and ALBERT PHILIPP BENDER, a citizen 5 of the Republic of Germany, and residents of Frankfort-on-the-Main, Hanauerlandstrasse 152/158, Germany, have invented certain new and useful Improvements in Relay Arrangements (for which we have filed an 10 application in Germany May 19, 1919, and July 24, 1919), of which the following is a specification.

This invention has for its object to do away with the inconveniences connected 15 with relays which are of such construction that, for their operation, a comparatively great energy is required. The invention relates to reverse-current relays which depend on temporarily-occurring directing forces 20 for current and voltage and which fail in almost all cases when, in consequence of short circuiting, the voltage of the line in proximity to the reverse-current relay has fallen to a value which is insufficient to operate the relay. This defect is overcome, according to the invention, by the arrangement 25 that the relay proper (for instance, a reverse-current relay) exerts only a very feeble effect which is just sufficient for the adjustment of the relay, the energy which is required for producing the contact being supplied by an auxiliary slowly acting device, e. g., by an overload-current time relay, 30 voltage-drop relay or the like. Owing to this arrangement, a secure contact will be obtained even if the directing forces at disposal in the reverse relay are very feeble only.

In order that the invention may be clearly 40 understood, I shall proceed to describe the same with reference to the two forms of construction of the improved relay shown, by way of example, in the accompanying drawing wherein:-

Fig. 1 shows the relay of one form of construction in the position of rest.

Fig. 2 is an intermediate position of said relay.

Fig. 3 shows the relay in the final or 50 circuit-closing position.

Fig. 4 represents, in side elevation, the relay of another form of construction in normal position.

Fig. 5 is a plan view of the device shown in Fig. 4. 55

Fig. 6 shows, in plan view, the relay in the final or circuit-closing position.

The reverse-current relay comprises a Ferraris disc *a* which is under the control of the current coil *b* and of the voltage coil *c*. According to the direction of the current, the hand *d* of the reverse relay *a* will slightly turn to the right or to the left. A stop *e* serves to stop the hand when the direction of current is normal. A contact *f* serves 60 for the reverse-current release. *g* is a time relay which is operated in any convenient manner, for instance, with the aid of an overload-current relay *2'* and which serves for completing a circuit to the relay *g*, thereby pulling a core *h* into a coil *i*. In the form of construction shown in Figs. 1 to 3, *h* is an extension of the time relay terminating in a point and designed to push side- 65 wise the hand *d* of the reverse-current relay *a*, if, during the operation of the time-lag relay, the current should be reversed. 70

When current traverses the circuit in the opposite direction so that the overload-current relay *g'* is operated and current is supplied to the time relay *g*, and the core *h* is pulled into the coil *i*, the pointer *k* moves upwardly and, as point *d* of the reverse-current relay has moved slightly to the left towards the contacts *f*, the pointer *k* pushes 80 said hand farther to the left. At the end of the operation, when the reverse current continues, (Fig. 3) the hand *d* has been pushed by the pointer *k* so far to the left that the contact for the release of the corresponding switch is established at *f*. 85

An especially good solution of the problem upon which the invention is based is obtained by the form of construction of the relay which is shown in Figs. 4 to 6 and in 95 which the auxiliary device serves to close directly a contractor *f*, which is possible, however, only when an insulating body, preventing the closing of the contractor *f* and controlled by the main relay, has moved 100 from its position between the contacts. In this form of construction, *a* is a reverse-current relay with the current coil *b* and with the voltage coil *c*, *d* is the hand upon the free end of which a plate *l* of insulating 105 material is fixed, *g* is the time relay whose

core *h* is to be pulled into the coil *i*. An extension *m* of the core *h* serves for closing the contactor *f* for tripping the circuit breaker.

- 5 At the normal position shown in Fig. 4, the time relay *g* is at rest. The insulating plate *l* of hand *d* stands between the two contacts of contactor *f*, as can be seen in Fig. 4. When reverse current traverses the 10 protected circuit, the relay *a* oscillates slightly. At the same time, the overload-current relay has been closed by the impulse from the excess current so that the coil *i* attracts the core *h*. When the reverse current continues, the contactor *f* will then be closed by the extension *m* of the core *h*, as the insulating plate *l* has moved away from 15 between the contacts *f* (Fig. 6). As can be seen from the drawing, a very feeble directing force is sufficient for the reverse-current relay *a*, as the work of closing the contactor *f* is done essentially by the time relay *g*. The arrangement of the relay as a switch for the starting of a contact closing is 20 advantageous also for other arrangements but for reverse current relays.

I claim:—

1. A relay comprising, in combination, a Ferraris disc, a control switch, a current-responsive coil connected in series in the line circuit, a voltage coil connected across the line, said disc being under the joint control of said coils and operated in one direction or the other depending upon the direction of current in the line, an overload relay connected in series in the line, a slow-acting device controlled by said overload relay and set in operation upon excessive current, and means actuated by said slow-acting device 30 and controlled by said Ferraris disc for operating said switch.
2. A relay comprising, in combination, a Ferraris disc, a current coil connected in series in the line, a voltage coil connected across the line, said disc being under the joint control of said coils and operated in one direction or the other according to the direction of current flow in the line, an overload relay connected in the line, a slow-acting device 40 controlled by said overload relay and set in operation upon excessive current flow, a switch adapted to be operated by said slow-acting device upon a predetermined

movement thereof, a member connected to said disc normally permitting circuit-interrupting operation of said switch, the operating member being adapted to move from operative position upon a reversal in the direction of current movement. 55

3. A relay comprising, in combination, a Ferraris disc, a control switch, an arm on the disc for engagement with the switch, a current-responsive coil connected in series in the line circuit, a voltage coil connected across the line, said disc being under the joint control of said coils and operated in one direction or the other depending upon the direction of current movement in the line, an overload relay connected in series 60 relation to the line, a long-time-element relay controlled by said overload relay upon the occurrence of excessive current in the line, a member constituting an element of, and actuated by, the long-time relay for exerting positive pressure on said arm, whereby said switch is operated upon the occurrence of a sustained reversal of current in the line. 70

4. A relay comprising, in combination, a Ferraris disc, a control switch, a pointed arm on the disc for engagement with the switch, a current-responsive coil connected in series in the line circuit, a voltage coil connected across the line, said disk being under the joint control of said coils and operated in one direction or the other depending upon the direction of current movement in the line, an overload relay connected in series relation to the line, a long-time-element relay controlled by said overload relay 80 upon the occurrence of excessive current in the line, a member constituting a pointed element of, and actuated by, the long-time relay for exerting positive pressure on said arm in a direction longitudinally of said arm and member, movement of the Ferraris disc determining whether the arm is moved into or out of operative engagement with the switch. 85

In testimony whereof we affix our signatures in presence of two witnesses:

PETRUS KLAAS VAN DER STERR.

ALBERT PHILIPP BENDER.
